UNITED STATES PATENT OFFICE.

LORING Q. WHITE, CISCO W. HART, AND HENRY O'DONNELL, OF BROCKTON, MASSACHUSETTS, ASSIGNEES TO L. Q. WHITE SHOE COMPANY, OF BOSTON, MASSACHUSETTS, A CORPORATION OF MASSACHUSETTS.

INNERSOLE.

1,115,757.

Specification of Letters Patent.

Patented Nov. 3, 1914.

Application filed August 15, 1914. Serial No. 856,895.

To all whom it may concern:

Be it known that we, LORING Q. WHITE, Cisco W. HART, and HENRY O'DONNELL, citizens of the United States, and residents 5 of Brockton, county of Plymouth, State of Massachusetts, have invented an Improvement in Innersoles, of which the following description, in connection with the accompanying drawing, is a specification, like 10 characters on the drawing representing like parts.

This invention relates to inner soles such as are used in the manufacture of welt shoes and has for its object to provide a satisfactory 15 inner sole which can be made from leather or other material that has not sufficient thickness or strength to permit the inseam-stitch-receiving lip to be formed by channeling the body of the inner sole from the margin or edge thereof and yet leave a marginal edge exterior to the lip having sufficient strength and stiffness to meet the requirements exacted of the edge of an 20 insole in the manufacture of a welt shoe.

One well-known type of inner sole that is commonly used in the manufacture of welt shoes is the so-called "gemmed" inner sole which is made from a piece of leather or similar material that is channelled at its 25 marginal edge to form a lip to which the welt and upper may be sewed, the lip and underside of the inner sole being covered with a layer of canvas. In an inner sole for welt shoes one necessary feature is a lip of 30 suitable strength to permit the welt and upper to be sewed thereto, and another necessary feature is the provision of a marginal edge outside of the lip which has sufficient 35 strength and thickness so that it will not give when it is acting as a guiding edge during the rough-rounding, Goodyear stitching, and other operations in the manufacture of the shoe, for if said marginal edge is lacking 40 in strength or rigidity it is liable to give 45 or yield under the pressure it receives from the guiding element of the machine during the above operations, and if this occurs the operations will not be properly performed. 50 For instance, if such marginal edge should 55 give or yield during the Goodyear stitching operation, the line of the outseam stitches would vary from the proper position and an imperfect shoe would be produced.

When the lip is formed by channeling the

body of the inner sole from the outer edge 55 thereof, the marginal edge will have a thickness less than the body of the inner sole, and in order to provide an inner sole made in this way with an edge of sufficient strength it is necessary to use a piece of 60 leather of considerable thickness. This fact prohibits the use of comparatively thin leather for inner soles that are channeled from the edge. So far as the function of the body of the inner sole is concerned a 65 satisfactory inner sole could be made from material which is comparatively thin, but if the inner sole is provided with a lip channeled from the edge thereof, it is necessary to use comparatively thick material in order 70 to provide an edge of sufficient strength.

By our invention we have provided for making an inner sole which has a marginal edge of requisite strength and a lip of the requisite size and strength from very thin 75 material, thereby enabling shoe manufacturers to use in the manufacture of inner soles material which they have heretofore been unable to use for this purpose.

In order to give an understanding of our 80 invention, we have illustrated in the drawings a selected embodiment thereof which will now be described after which the novel features will be pointed out in the appended claim.

In the drawings, Figure 1 is a plan view 85 of an inner sole embodying our invention; Fig. 2 is an enlarged section on the line $x-x$, Fig. 1; Fig. 3 is an enlarged sectional view showing the manner in which the welt 90 and upper are united to the rib.

In the drawings, the body of the inner sole is shown at 1 and it may be made of any suitable material. This body portion is channelled, as at 2, thereby to form a lip 3, 95 the channel 2 being situated at a suitable distance in from the edge or periphery 4 of the body 1, so that the portion 5 of the body between the channel and the exterior edge 4 is of the full thickness of the body. 100 In the manufacture of welt shoes it is necessary that the marginal edge of the inner sole should have a certain amount of rigidity and strength, and with our invention it is possible to use any material, no matter how thin, so long as the full thickness of the material will give a sufficiently strong 105 marginal edge. Where the body 1 is made

- of comparatively thin material the lip 3, which is cut by forming a channel 2, must of necessity be considerably thinner than the body portion 1, and will, therefore, be too thin and weak to form an anchor for the inseam stitches 6 that unite the upper 7 and welt 8 to the inner sole. This is especially true if the material of the body 1 is of a more or less spongy nature.
- 10 In order to provide a proper rib or lip for the inseam stitches, we propose to reinforce the lip 3, formed by making the channel 2, by inserting in the channel 2 on the exterior of the lip a reinforcing member 80 herein shown in the form of a cord, although a strip 80 of any material could be used for this purpose. This strip or cord 80 will preferably substantially fill the channel 2 and lie against the outside of the lip 3, and it may be cemented to the lip 3 or may merely be laid in place. After the member 80 is laid in the channel 2 against the lip 3, the inner sole is gemmed by applying to the face thereof a covering 9 of fabric as usual in the manufacture of so-called "gemmed" inner soles, and this fabric overlies and embraces the compound rib or lip formed from the lip 3 and the cord 80. The fabric 9 will be cemented to the body of the inner sole as usual. An inseam-stitch-receiving rib 11 is thus formed by the lip 3, cord 80 and covering 9 of canvas which is strong and solid and in which the inseam stitches 6 can be securely anchored, and in the formation of this rib, the edge portion 5 of the sole is not weakened in any way, but has all the strength provided by the entire thickness of the body 1. An inner sole made in this way can be made of comparatively thin material because the edge 5 contains the full strength of the material and is not weakened in forming the lip. Furthermore, by locating the cord 80 on the exterior of the lip 3, the latter constitutes a positioning member or abutment which serves to hold the cord 80 in place as the inseam stitches are inserted.
- In the operation of making a welt shoe the needle 12 is inserted through the inseam-stitch-receiving rib or lip 11 from the outer edge of the shoe and the location of the cord 80 on the exterior of the rib 3 has the advantage that the penetrating thrust of the needle serves to force the cord 80 more closely against the lip 3, thus preventing any

undesirable separation of these two parts as the line of stitching 6 is made.

It will be noted that in this invention the cord 80 is held in position against the rib 3 by the overlying fabric 9, this being sufficient in view of the fact that the penetrating thrust of the needle has no tendency to separate the cord 80 from the lip 3, but rather tends to force them together, a feature which is desirable. Another advantage of having the cord 80 on the outside of the lip 3 is that said lip gives the rib 11 a firm inner face for the awl of the inseam-stitching machine to act on in feeding the shoe during the stitching operation, and a firm line or surface for the channel guide to follow. Furthermore, said lip 3 supports the fabric 9 on the inner face of the rib 11 and prevents the fabric from being drawn in under the cord on the inside thereof by the stitches 6, a proceeding which would be liable to tear or injure the texture of the fabric and thus weaken the insole.

Instead of being made of a single thickness of leather, an insole embodying our invention may be made of several superposed plies of very thin material cemented or otherwise secured together.

We claim:

An inner sole having a body portion 85 channeled at a distance from its edge in such manner as to form an upturned cord-positioning lip at the inner edge of said channel, the edge portion of the inner sole exterior to said channel having the full 90 thickness, strength and rigidity of the body portion, a cord laid in the channel against the outer face of the lip, and a fabric layer 95 covering the channeled face of the body, the lip and the cord, thereby to form an inseam-stitch-receiving rib, said lip acting to prevent the cord from being displaced by the penetrating thrust of the needle during the formation of the inseam stitches by which the upper and welt are secured to 100 the rib.

In testimony whereof, we have signed our names to this specification, in the presence of two subscribing witnesses.
